(74) Attorney, Agent, or Firm—Foley & Lardner

(57) **CLAIM**

The ornamental design for a chair, as shown and described.

DESCRIPTION

FIG. 1 is a front perspective view of a chair according to an exemplary embodiment.

FIG. 2 is a left side elevation view of the chair.

FIG. 3 is a front elevation view of the chair.

FIG. 4 is a top plan view of the chair.

FIG. 5 is a rear elevation view of the chair.

FIG. 6 is a bottom plan view of the chair; and, FIG. 7 is a front perspective view of the chair showing an alternative environment.

The broken line disclosure is for illustrative purposes only and forms no part of the claimed design.

1 Claim, 4 Drawing Sheets

FIG. 3

FIG. 4

FIG. 5

FIG. 6

FIG. 7
